(57) CLAIM

The ornamental design for a television antenna, as shown and described.

DESCRIPTION

FIG. 1 is a perspective view of a television antenna showing our new design.

FIG. 2 is a top plan view thereof.

FIG. 3 is a front elevational view thereof, the rear elevational view being identical thereto.

FIG. 4 is a bottom plan view thereof.

FIG. 5 is a right side elevational view thereof; and, FIG. 6 is a left side elevational view thereof.
